UNITED STATES PATENT OFFICE.

ALPHEUS E. HOLCOMB, OF CHICAGO, ILLINOIS, ASSIGNOR OF ONE-HALF TO FRANCIS M. JOHNSON, OF OREGON, ILLINOIS.

EXCAVATING-BUCKET.

No. 918,552.

Specification of Letters Patent.

Patented April 20, 1909.

Application filed July 14, 1908. Serial No, 443,486.

To all whom it may concern:

Be it known that I, ALPHEUS E. HOLCOMB, a citizen of the United States, residing at Chicago, in the county of Cook and State of Illinois, have invented new and useful Improvements in Excavator-Buckets, of which the following is a full, clear, concise, and exact description, reference being had to the accompanying drawing, forming a part of 10 this specification.

My invention relates to improvements in excavator buckets, and has for one of its objects to provide a bucket which, while having all the advantages of a face-digging bucket, will possess the additional advantage of being adapted to travel vertically, or substantially vertically, without losing its load, and which, at the same time, may be automatically dumped.

20 I have illustrated in the accompanying drawings one form which my invention may take.

In said drawings—Figure 1 is a face view of a bucket ladder carrying my improved bucket; Fig. 2 is a side elevation of my improved bucket; Fig. 3 is a plan view of my improved bucket; Fig. 4 is a detail view of the hinged connection for the bottom of the bucket; Fig. 5 is a sectional view taken on the line 5—5 of Fig. 4; Fig. 6 is an end view of the hinge illustrated in Fig. 4; Fig. 7 is a sectional view taken on the line 7—7 of Fig. 1; Fig. 8 is a sectional view on the line 8—8 of Fig. 7; and Fig. 9 is a sectional view on the line 9—9 of Fig. 7.

In carrying out my invention I provide a bucket ladder, which may be of any suitable form, for carrying the traveling conveyer on which the buckets are mounted. The 40 ladder illustrated in the drawings comprises a pair of side frames 2 and 3, formed of angle irons, between which the rotating tumblers for the conveyer are supported upon suitable shafts. In the form of the 45 ladder illustrated I have shown carried thereby a pair of upper tumblers 4, two pairs 5 and 6 of intermediate tumblers, which are arranged relatively to the upper tumblers to cause the conveyer, when traveling at the upper end of the ladder, to assume a substantially horizontal position; one pair 7 of secondary intermediate tumblers, which are arranged relatively to the pair of bottom tumblers 9 in such a manner 55 that the conveyer will be given the proper

slant for cutting the face of the ditch; a pair 8 for supporting the conveyer on the upper side of the ladder; and a pair of bottom tumblers 9. The conveyer for carrying the buckets comprises a pair of chains 10, 60 which are adapted to travel over the tumblers above mentioned, and on the digging face of the ladder are adapted to travel in a pair of guides 11, which hold the buckets in a rigid digging position. The upper tumbler 65 4 is preferably the driving tumbler for the chain, and receives its motion by means of a beveled gear connection 12 between the shaft 13 of the tumbler and a suitable driving shaft. The shaft 13 of the tumbler is also 70 provided with a fixed scraper 14, which projects horizontally from the upper end of the bucket ladder and in a position to enter and clean each bucket as it is dumped.

A plurality of buckets 15 are secured between the traveling chains 10. Each bucket comprises a curved bottom 16, two sides 17 and a hinged back 18. This construction leaves the top and front of the bucket open. For hinging the back 18 to the bucket I provide on the bottom 16 a pair of castings 19, having openings therein in which fit the ends of a bearing rod 20. The extreme outer ends of the rod are flattened, as at 21, and that portion of the openings in the castings 85 in which these ends fit is correspondingly shaped to prevent the rod from turning. A journal bushing 22 fits over the bearing rod 20 and at its outer end is secured in a pair of castings 23, bolted or otherwise fastened 90 on the back 18. The outer ends of the bushing 22 are also flattened, as at 24, to prevent the bushing from turning relatively to the back 18. By this arrangement a hinge for the back is provided which has a large bearing 95 surface. The castings 19 are provided with rearwardly extending stops 25, which limit the opening movement of the back 18, and it will be noted that when the back is opened to its full extent it forms practically 100 a continuation of the bottom 16. The advantage of this arrangement will be more apparent hereinafter.

For holding the back 18 of the bucket closed, I provide on each side of the bucket 105 a latch 26, pivoted at 27 and having at its rear end a catch or hook 28 for engaging a projection 29 secured on the back of the bucket. The opposite end of the latch is extended, as at 30, to provide a means 110

whereby the hook 28 may be disengaged, to permit the back to open. Each of the pair of tumblers 9, 6 and 4 are respectively provided with cam members 31, 32 and 33 for operating the latch 26.

For the purpose of describing the operation of my bucket, we will describe a complete cycle of one bucket, and assume that the cycle starts just before the bucket reaches its dumping point. As the bucket nears its dumping point it passes over the tumbler 4, and one of the cams 33 on each of the pair of tumblers engages the projecting portions 30 of the latches 26, forcing this end of the latches downwardly, which causes the opposite ends to be moved upwardly and become disengaged from the projections 29 on the back of the bucket. In its continued movement over the tumbler the bucket assumes a vertical position and the weight of the dirt or material in the bucket forces the back open and the load is dumped. As the bucket travels over the tumbler 4, the scraper 14 enters the same and clears the bucket of any dirt or material which has adhered to the inner surface of the bottom and back of the bucket. As before mentioned, the back of the bucket, when opened, forms a continuation of the curved bottom of the bucket. By this arrangement the back forms no obstruction to the scraper 14 and the bucket will continue in its travel over the tumbler without hindrance. On its return travel to the bottom of the bucket ladder, it will be noted that the position of the bucket is reversed. Gravity will, therefore, cause the bottom of the bucket to drop closed, and as the bucket passes beneath or around the pair of lower tumblers 9, the cams 31 on these tumblers will engage the latches 26 and move them closed or into engagement with the projections 29 on the bottom of the buckets. At this point the bucket commences to dig and the weight of the material in the bucket will prevent the catch from becoming disengaged. It will also be noted that as the bucket moves on its upward travel again the latches 26 are on the upper side of the bucket, and gravity will also tend to hold the same closed.

The above is a description more particularly of the operation of the bucket in dry land work. In operating the bucket in water, or under water, the water tends to keep the back from closing. Therefore, in operating in water I provide a spring 34, which tends to hold the latch normally closed, so that the back is fastened before entering the water. When the spring is provided, as the bucket is dumped and after the latch has moved out of engagement with one of the cams 33, the spring will pull the latch into closed position before the bottom of the bucket can drop shut; therefore, as the bucket moves over the pair of tumblers

6, one of the cams on each of the tumblers will engage the projecting end 30 of the latch, again forcing the latch open, and as the bucket assumes a substantially vertical position on its return travel, the bottom will drop shut, so that when the bucket passes off of the tumblers 6 the spring on the latch will pull the same closed over the projection 29.

Having thus described my invention, what I claim as new and desire to secure by Letters Patent, is:

1. The combination with a bucket ladder, of a bucket traveling thereon and having a portion adapted to open, means for automatically causing said portion to open to dump the bucket, and means whereby said portion is automatically closed after the bucket has been dumped.

2. The combination with a ladder, of a bucket traveling thereon and having a portion adapted to open, and means for automatically opening the portion, cleaning the bucket and closing said portion.

3. The combination with a bucket ladder, of a bucket traveling thereon having a curved bottom and an opening back, the curve of the bottom and the back, when opened, having its center on the center of the tumbler over which the bucket passes at a dumping point.

4. The combination with a bucket ladder, of a bucket traveling thereon having a curved bottom and an opening back, the curve of the bottom and back, when opened, having its center on the center of the tumbler over which the bucket passes at its dumping point, and a scraper adapted to enter and clean said bucket.

5. The combination with a bucket ladder, of a bucket traveling thereon having a curved bottom and an opening back, the curve of the bottom and back, when opened, having its center on the center of the tumbler over which the bucket passes at its dumping point, and a stationary cleaner over which said bucket is adapted to pass.

6. The combination with a bucket ladder, of a bucket adapted to travel thereon having a back adapted to open, a latch for holding the back closed, automatically operated means for disengaging the latch to permit the back to open, said back being adapted to close by gravity, and automatically operated means for causing said latch to engage to hold the back closed.

7. The combination with a bucket ladder having an upper tumbler and a lower tumbler, of a bucket traveling on said ladder having a back adapted to open, a latch for holding said back closed, automatically operated means for disengaging said latch to permit the back to open, said back being adapted to close by gravity, and automatically operated means for closing said latch.

8. The combination with a bucket ladder having an upper tumbler and a lower tumbler, of a bucket traveling on said ladder having a back adapted to open, a latch for holding said back closed, automatically operated means for disengaging said latch to permit the back to open, said back being adapted to close by gravity, automatically operated means for closing said latch, and means for normally holding said latch closed.

9. The combination with a bucket ladder having an upper tumbler and a lower tumbler, of a bucket traveling on said ladder having a back adapted to open, a latch for holding said back closed, automatically operated means for disengaging said latch to permit the back to open, said back being adapted to close by gravity, and automatic-

ically operated means for closing said latch, said latch being adapted to be normally held 20 closed by a spring.

10. In a traveling bucket, the combination with a body portion, of a portion adapted to open, and means for hinging said portion to the body portion, comprising a bearing 25 rod rigidly secured to said body portion and a journal sleeve journaled on said rod and rigidly secured to said opening portion.

In witness whereof, I have hereunto subscribed my name in the presence of two wit- 30 nesses.

ALPHEUS E. HOLCOMB.
